SUPERHEATER BOILER

John A. Barnes, Chappaqua, N. Y., assignor to
The Superheater Company, New York, N. Y.

Application February 27, 1932, Serial No. 595,496

10 Claims. (Cl. 122—473)

My invention relates to steam generators and has as its principal object the provision of a boiler having comparatively high generating capacity per unit of volume together with good efficiency.

It is often desirable to place a boiler in a limited space so that the output per unit volume of the boiler is the main consideration in selection of the design. It is nevertheless always desirable to maintain good efficiency if possible. I disclose hereinbelow in connection with the accompanying drawings, a design of boiler adapted to operate satisfactorily in a limited space such as that available in an electric locomotive while having also a high efficiency and high output per unit volume. The novel features of my invention are pointed out in the appended claims. In order, however, that the invention may be fully and clearly understood, I have illustrated in detail in the accompanying drawings a boiler in accordance with my invention which has been selected by way of example from a number of possible embodiments of the invention, and the following detailed description is given in connection with said drawings. In the drawings,

Fig. 1 is a front elevation of a boiler in accordance with my invention, parts being broken away for purposes of illustration.

Fig. 2 is a plan view of a boiler shown in Fig. 1. Fig. 3 is a vertical section on line 3—3 of Fig. 2, parts being broken away for purposes of illustration.

Fig. 4 is a vertical section at right angles to Fig. 3 taken on the line 4—4 of Fig. 3.

Fig. 5 is a sectional plan view taken on the line 5—5 of Fig. 3, the front face of Fig. 5 being at the right.

The boiler illustrated in the drawings comprises four sections each of which has an upper steam and water drum and a lower water drum connected by a bank of substantially vertical tubes. The four banks thus provided are arranged to enclose a combustion chamber 9 which is squared in horizontal cross section. The face of the boiler appearing in Fig. 1 is considered as the front and has a steam gage 10 and a water column 12 thereon. Parts of five of the eight drums of the boiler appear in Fig. 1, these being the steam and water drum 14 of the front section of the boiler, the water drum 16 of the front section of the boiler, the steam and water drum 14a of the left section of the boiler, the water drum 16a of the left section of the boiler and the water drum 16b of the right section of the boiler. All four steam and water drums of the

boiler appear in dotted lines in Fig. 2. In addition to the steam drums 14 and 14a, Fig. 2 shows the right hand steam and water drum 14b and the rear steam and water drum 14c. All the corresponding water drums appear similarly in Fig. 5, this figure showing, in addition to the drums 16, 16a and 16b previously mentioned, the rear mud drum 16c. Each water drum is connected to its corresponding steam and water drum by a bank of tubes. The bank connecting the front pair of drums 14 and 16 is designated by reference character 18, the left hand, right hand and rear banks being designated by the characters 18a, 18b and 18c respectively.

The four sections, each having an upper and lower drum, are connected together so as to act as a unit by connections between adjacent ends of the drums. As appears in Fig. 1, steam drum 14 is connected to steam drum 14a by a pipe 20 making a 90 degree bend and connecting the two drums below the water level. A similar pipe 22 connects the two drums 14 and 14a above the water level. A third pipe, 24, connects the front and left sections between the mud drums 16 and 16a. All three of the curved pipes 20, 22 and 24 have joints whereby they may be readily disconnected from the drums to facilitate the erection or taking down of the boiler and the cleaning of the connecting pipes. A group of pipes similar to pipes 20, 22 and 24 connects ends of drums 14 and 16 to drums 14b and 16b. Another such group connects the ends of drums 14a and 16a to drums 14c and 16c, while a fourth group connects drums 14b and 16b to drums 14c and 16c. Appropriate reference characters are applied to such curved connecting tubes where ever they appear in the drawings, although not all of them are visible in the drawings.

The four sided boiler formed by the four banks of tubes indicated above is supported on a base. Such base is designated by characters 30 and has four cradles adapted to fit portions of the surfaces of the mud drums 16, 16a, 16b and 16c. Two of the cradles in the base 30 are shown at 32a and 32b, Fig. 4. The other two cradles are shown at 32 and 32c, Fig. 3. It is intended that the boiler illustrated in the drawings be adapted for use on electric locomotives or in other places where the base of the boiler may be subject to shocks and oscillations. I have, therefore, provided means whereby the boiler is held securely in place, but may be readily removed from the base 30 whenever desired. For this purpose each of the four mud drums 16, 16a, 16b and 16c has one or more brackets 34 fixed to its underside, 110

brackets 34 having projecting fingers 36, 36 thereon arranged to receive pivoted pins or eye-bolts 38. The cradles 32, 32a, 32b and 32c are broken out at the locations of the brackets 34, but the 5 base extends beneath such brackets and is provided with openings 38a to receive the bolts 38 so that the boiler may be securely clamped to the base 30 by means of the usual nuts on the ends of the bolts 38, but may be easily released so as 10 to be withdrawn from the base when desired.

The combustion chamber 9 is covered by a roof 40 which rests on the top drums 14, 14a, 14b and 14c. As shown in Fig. 3, the front drum 14 and rear drum 14c have angles 41, 41 fixed thereon 15 which engage the sides of the outer tiers of blocks of which the roof 40 is composed, so as to throw a portion of the weight of the roof on the front and rear drums. In order to sustain the thrust of the roof and also to protect the roof 20 against undue radiation, diagonal tubes 42 and 42a are provided, tubes 42 connecting into the rear lower drum 16c and the upper front drum 14 and tubes 42a connecting into the lower front drum 16 and the upper rear drum 14c. The 25 thrust of the roof 40 against the upper side drums 14a and 14b is resisted by economizer tubes 44, 44 which are embedded in the roof and extend horizontally transversely to the diagonal tubes 42 and 42a at a level immediately above the drums 14a 30 and 14b so that the ends of the tubes 44 may be conveniently secured to the drums 14a and 14b by straps 46, 46. The economizer tubes 44 therefore not only conserve heat but protect the roof from over-heating and act as structural elements 35 to tie together the top drums of the boiler.

In order that the volume of the combustion chamber 9 may be utilized to best advantage, the generating tubes are so arranged that the products of combustion can pass from the chamber 9 40 into the banks 18, 18a, 18b and 18c only near the top of the chamber. Any unburned gases are thereby prevented from becoming chilled by contact with the generating tubes, the path of the gases being such that ample time for combustion 45 is provided even at high rates of combustion. These results are obtained by arranging the lower portions of the tubes 42 and 42a in the same plane with the front row of the tube rows 18 and 18c from the level of the lower drums 16 and 16c to a point well above the centre of the combustion chamber. The vertical portions of 50 tubes 42 and 42a therefore form, with the front rows of tubes of banks 18 and 18c, baffle walls 48 and 48c preventing the gases from passing directly into the generating banks and forcing them to travel upward in the combustion chamber to a level above the bends in tubes 42 and 42a before entering the banks. Similar baffle walls 48a and 48b are formed on the other two sides of the 55 chamber 9 by arranging the tubes in the front rows of the banks 18a and 18b close together from the level of the lower drums 16a and 16b up to a point above the centre chamber 9, but running alternate tubes in such front rows in a plane 60 in front of the others for about the upper third of their lengths to permit gases to flow into the banks. The front faces of the baffle walls 48, 48a, 48b and 48c, are, however, exposed to intense radiation and generate steam at high 65 rates whenever the boiler is being forced. I prefer therefore to make the tubes 42, 42a and those in the front rows of tube banks 18, 18a, 18b and 18c of larger size than the remainder of the generating tubes, as is most clearly shown in Fig. 5.

70 The combustion chamber 9 extends down be-

low the level of the mud drums 16, 16a, 16b and 16c into the base 30, the floor of such chamber and the inner face of the base 30 having a covering 49 of fire-brick or other suitable refractory.

A burner 93 is arranged at one corner of chamber 9 at a level below the mud drums so as to discharge substantially horizontally at the diagonally opposite corner. The refractory 49 is therefore highly heated and the radiation therefrom not only causes a high steaming rate in the tubes of the baffle wall sections 48, 48a, 48b and 48c, but assists in the complete combustion of the fuel so that scarcely any smoke is observable even when the furnace is operating at a rate of 200,000 B. t. u. per cubic foot of furnace volume, provided the burner is adapted to thoroughly atomize the fuel at the higher rates of combustion.

After passing into tube banks 18, 18a, 18b and 18c, the gases are directed downward by baffles 50, 50a, 50b and 50c respectively. Such baffles are placed somewhat to the outside of the centre lines of the banks of the generating tubes and extend as solid plates downwardly from the upper drums 14, 14a, 14b and 14c for a suitable distance. As shown, the plates forming baffles 50, 50a, 50b and 50c are cut out at a point above the lower drums about one-fifth of the distance between the lower and upper drums to permit the gases to pass around their lower edges. Legs 52, 52, however, are provided for each of baffles 50, 50a, 50b, 50c, such legs preferably being formed as integral extensions of the baffles and extending downwardly to contact with the upper surfaces of water drums 16, 16a, 16b and 16c to support the baffles thereon. The outer rows of the 100 generating banks 18, 18a, 18b and 18c likewise are set close together for the major portion of the distance from the lower to the upper drums, but such rear rows are opened up for a sufficient distance below the top drums 14, 14a, 14b and 14c 105 so that the gases can pass upwardly on the outer sides of the baffles and then pass out of the banks near their upper outer corners and so around the outer faces of the upper drums into flues 53, 53a, 53b and 53c, such flues leading into a 110 common gas chamber 54 above the roof 40. From the chamber 54 the gases pass into an uptake 56. The uptake 56 is shown as near the front of the boiler but it will be understood that it may be placed wherever convenient, the location of the uptake 56 in the present drawings being that adapted for a particular installation and due to reasons peculiar to such installation.

Feed water for the boiler illustrated in the drawings is supplied through a pipe 58 at the rear right hand corner of the boiler as viewed from the front. From the pipe 58 the water passes through the economizer tubes 44 in series to a point 60 at the front left hand corner of the boiler. From the point 60 feed water is conducted downwardly from the level of the roof through a pipe 62 to a distributing pipe 64, one branch of which runs across the front face of the boiler somewhat above the level of the drum 16 and turns downwardly through a valved connection 66 so as to deliver into the connecting pipe 24a between the drum 16 and drum 16b. The other branch of the distributing pipe 64 runs along the left side of the boiler along the outer side of the generating bank 18a so as to connect with the water connection 24c between drums 16a and 16c at point 66a (Fig. 5). It will be seen that the feed water is arranged to enter the boiler at diametrically opposite points and all four sec-

tions therefore are supplied equally regardless of steaming conditions.

Steam is taken off of each of the top drums 14, 14a, 14b and 14c through steam connections 68, 5 68a, 68b and 68c (Figs. 1 and 2). Such steam connections lead downwardly at the corners of the boiler and connect through releasable joints with the lower ends of superheaters. Two such removable joints are shown at 70 and 70a, Fig. 10 1, the other two not being illustrated in the drawings but being similar to joints 70 and 70a. The superheaters for each of the banks are alike and are designated by reference characters 72, 72a, 72b and 72c respectively. The superheaters lie 15 adjacent the inner faces of baffles 50, 50a, 50b and 50c. The tubes of each of the banks 18, 18a, 18b and 18c are arranged, as clearly appears in Figs. 3 and 4, to provide space for receiving such superheaters, the spaces for the superheaters 20 running parallel to the drums of the several sections of the boilers and also vertically parallel to the generating tubes so that the superheaters can be inserted into the banks from their edges, the four sections of which the boiler is composed 25 being of the same size and coming together at their inner faces so that a notch or cut-out 73 is provided at each corner of the boiler permitting the ready insertion and removal of the superheaters to and from the banks 18, 18a, 30 18b and 18c whenever the outer covering 74 is removed.

It is apparent from the drawings that the superheaters 72, 72a, 72b and 72c are individual to the banks 18, 18a, 18b and 18c respectively. Each 35 such superheater is formed of piping arranged in serpentine form, as best appears in Fig. 3. Each superheater is provided with a pair of bars 76, 76 which lie against the inner face of one of the baffle plates, such as 50, and the piping of 40 each superheater is fastened to the bars 76 by means of U-bolts 78 or other suitable fastening elements, the bars 76 extending downwardly so as to rest on the top surfaces of the mud drums 16, 16a, 16b and 16c respectively. It will be seen 45 that the bars 76 transfer the weights of the superheater sections to the drums without their falling on the generating tubes. The upper ends of the bars 76 moreover are bent away from the plates 50, 50a, 50b and 50c, as indicated at 80, 80 50 (Figs. 3 and 4) whereby the bars are held against movement in the direction away from the plates 50 by contact with the tubes in one of the rows in the generating banks 18. The lower ends of the bars 76 also contact with the tubes in the 55 same row as the tops of the bars so that the superheater is braced against vibration in both directions, movement in one direction being prevented by contact of the bars 76 with the generating tubes and the movement in the opposite 60 direction being prevented by contact of the bars 76 with plates 50 which lie in turn in contact with another row of generating tubes. Vibration such as that of a locomotive is thereby prevented from 65 loosening the joints at the ends of the superheaters. However, as the weight of the superheater units does not fall on the generating tubes, there is not enough pressure against such tubes to cause leakage at their joints with the drums.

The steam enters each superheater at its lower 70 end and leaves it at its upper end. For collecting the superheated steam I provide a header 82 which surrounds three sides of the boiler, extending along its rear and two lateral faces. The upper ends of the serpentine pipe of each of the 75 superheaters connect into boxes 84, 84a, 84b and

84c, one of which appears in elevation in Fig. 1. Such box opens at its top and connects to an elbow such as 86a by means of a releasable joint 88. A second joint 90 connects the elbow 86a with the header 82. The superheater for the front generating bank 18 connects with the lateral branch of the header 82 at the right hand front corner of the boiler; the superheater for the bank 18a connects with the other lateral branch of the header 82 at the left-hand front corner of the boiler; the superheater for the bank 18b connects with the header 82 through a Y-fitting 88B at the rear right-hand corner of the boiler; and the superheater for the bank 18c connects with the header 82 through a Y-fitting 89 at the left rear corner of the boiler, left and right being taken as when looking from the front of the boiler. The steam offtake from the boiler is shown as passing from the header 82 at the point 90. A safety-valve connection leads from header 82 at point 192 and another safety-valve connection 194 leads from drum 14.

The boiler herein disclosed is intended to utilize liquid or pulverized fuel. The burner 93 for such fuel can be arranged conveniently to discharge 100 into the combustion chamber immediately above the upper edge of the base 30 through a space such as 94 (Fig. 4) provided by the curvature of two of the lower drums 16 due to the fact that such drums are substantially in contact along 105 their inner elements at the level of their central axes. Below such level two adjacent drums curve away from each other at the corners to form an opening adapted to accommodate a burner.

Burner 93 discharges close to the refractory 110 lining and floor 49 so that such refractory becomes highly heated and promotes the combustion of the fuel from burner 93. The burner is in such position that its flame radiates strongly 115 against the baffle walls 48, 48A, 48B and 48C and the radiation from the hot refractory 49 also largely strikes the walls 48 and assists in increasing the amount of heat absorbed by such walls as radiant energy, thereby decreasing the temperature of the gases leaving the combustion 120 chamber. A boiler in accordance with my invention therefore has high efficiency over a wide load range even though using a moderate number 125 of rows of tubes in the convection banks.

What I claim is:

1. The combination with a boiler having an upper steam and water drum, a lower water drum, a bank of vertical tubes connecting said drums, said bank having a substantially vertical space therein open at the end of the bank, of a supporting means in said space resting on said water drum and arranged to divert the weight thereon substantially entirely away from said tubes, and a superheater having coils fixed to said means, said supporting means and superheater forming a unit adapted for easy removal from said space.

2. A boiler having four sections forming in plan the sides of a rectangle, a feed water heater having a rectangular plan and set above said sections, means for feeding water into said heater, and connections for leading water from the outlet of said heater into two diametrically opposite points in the boiler.

3. The combination of a boiler having four sections forming a rectangle in plan, water connections between said sections, and means for equalizing the steam pressure in said sections, and means for introducing feed water into the

80

boiler at two diametrically opposite corners of the rectangle.

4. The combination of a base having cradles on its upper portion, a boiler having water drums at its lower end adapted to rest in said cradles to support the boiler, said drums having brackets fixed to their lower surfaces, bolts pivoted to said brackets, said cradles having apertures therein adapted to receive said bolts, and nuts 10 on the lower ends of said bolts for clamping said drums to said cradles.

5. A boiler having a plurality of sections each including a bank of generating tubes and arranged around a combustion chamber, said banks 15 having their inner faces in juxtaposition whereby cut-out notches are provided at the corners of the boiler, said banks further having spaces extending therethru and opening to said notches and superheaters removably supported in said 20 spaces whereby such superheaters may be inserted into said spaces between the ends of any two adjacent banks.

6. The combination of a boiler having a bank of substantially vertical generating tubes, drums 25 at the upper and lower ends of said tubes, and a baffle plate in said bank and having a cut out lower section for the passage of gases and resting directly on the lower drum.

7. The combination as set forth in claim 6, together with standards in front of the baffle plate

and also resting directly on the surface of the drum and a superheater secured to said standards.

8. The combination as set forth in claim 6, together with standards in front of the baffle plate and also resting directly on the surface of the lower drum, and a superheater secured to said standards, the generating tubes of the boiler, the plate and standards being arranged to bear against each other near the ends of the generating tubes to minimize lateral vibration. 80 85

9. The combination of a boiler having a bank of substantially vertical generating tubes, drums connected to the upper and lower ends of said tubes, a supporting cradle beneath said lower drum, a superheater arranged in said bank, and supporting means for said superheater arranged to transmit its weight to said lower drum and to divert such weight from the generating tubes. 90

10. The combination of a boiler having four sections arranged to enclose a space having a rectangular plan view, each of said sections having a substantially vertical bank of generating tubes and upper and lower drums, diagonal tubes connecting two opposite lower drums with two opposite upper drums, and a roof structure including feed heater tubes secured to the other two upper drums. 100 105
